UNITED STATES PATENT OFFICE.

EDWARD L. HOGAN, OF DETROIT, MICHIGAN, AND GEORGE S. WITHAM, JR., OF HUDSON FALLS, NEW YORK, ASSIGNEES TO AMERICAN BLOWER COMPANY, OF DETROIT, MICHIGAN, A CORPORATION OF NEW YORK.

DRYING AND VENTILATING METHOD AND APPARATUS FOR MATERIAL-DRYING PLANTS.

Application filed May 8, 1924. Serial No. 711,859.

This invention relates to an improved drying and ventilating method and apparatus for material drying plants, particularly paper drying and analogous plants.

5 In paper drying plants and other manufacturing plants employing various kinds of drying apparatus and open treating vats, large volumes of hot vapor and steam are given off from the drying machine, vats, or 10 the like, filling the machine room with heavy moisture laden air, a condition highly objectionable to operatives and harmful to the building and equipment. Also, in the 15 case of paper driers and the like, the hot moist air pervading the machine room materially slows up the drying process and results in uneven drying of the web due to condensation thereupon and reabsorption of moisture thereby.

20 As will be readily appreciated when the exhaust hot air and vapor are permitted to escape outside the drying plant to the atmosphere, the waste heat is enormous, especially so in the operation of paper drying plants 25 in which it is common practice to supply heated air to the machine to assist in the drying operation.

It has heretofore been proposed to remedy these conditions by circulating such a large 30 volume of heated air throughout the whole machine room as to maintain a relatively dry condition of the air in the machine room after the same mixes with the vapors given off from the drier but the expense of fuel 35 necessary to supply the large amount of heated air required during cold weather renders such a system wholly impracticable. Another suggested method is to supply heated air in a plurality of blasts laterally 40 of the rolls at localized points at the vapor pockets between the rolls, and to use a hood disposed over the upper side of the rolls to collect the exhaust vapor but while it is advantageous to provide currents of heated air 45 laterally of the rolls in effecting the dissipation of the vapor from the pockets between the rolls and in assisting in the drying operation, this method is manifestly unsatisfactory for with the air blasts delivering 50 laterally of the rolls, a large part of the exhaust vapors will not be caught by the hood arranged over the rolls and will escape from the side of the rolls into the machine room.

Methods have also been devised for the purpose of recovering heat from the exhaust 55 vapors, but by these prior systems only a relatively small proportion of the heat of the exhaust vapors is reclaimed.

The object of the present invention is to overcome the difficulties hereinbefore referred 60 to; to prevent the escape of the exhaust vapors into the machine room with the consequent injury to the building structure and equipment, and the attendant unsatisfactory 65 atmospheric conditions for workmen; to prevent condensation upon and re-absorption of moisture by the material; to provide for a more expeditious, uniform and efficient drying 70 of the material, and also to recover and utilize a large proportion of the heat of the 75 exhaust vapors, whereby a considerable saving in the operating expense of such plants will be effected, the output increased, and a superior product obtained.

In accordance with our improved method, 75 a flow of heated air is provided transversely of the paper drying machine or the like, provision is made for preventing escape of vapor from the top of the machine into the machine room while providing against condensation of vapor at the upper side of the rolls, and the exhaust hot air and vapor is trapped and conducted off from the other side of the machine. The exhaust hot air and vapor is passed through a chamber, and 85 water in a finely divided condition is circulated within the chamber in the path of the exhaust hot air and vapor to effect a thorough transference of the heat of the exhaust vapors to the water, and the drying 90 and conditioning of the air for reuse. The heated water is utilized for various manufacturing operations about the plant or for heating or other purposes, and the dried air after the treatment within the chamber, is 95 re-heated, and returned to the drying machine for use over again for drying purposes. The invention contemplates maintaining a lateral flow of a relatively high volume of heated air completely about the heated rolls 100 and throughout the web, as distinguished from supplying heated air in a multiplicity of jets or blasts at localized points at the vapor pockets, and the exhaust hot air and vapor is prevented from escaping into the 105 machine room, all of the exhaust hot air

and vapor being trapped, conveyed off and treated to reclaim the heat therefrom and to recondition the air for use over again, the atmosphere of the machine room being 5 kept entirely free from the exhaust vapors. Any conventional form of heating means is employed for maintaining the desired room temperature in the machine room. The heated air supplied to the drying machine 10 is of a higher temperature than that required for the air of the machine room, and the invention contemplates mixing some of the air from the machine room with air of a higher temperature and supplying the resultant 15 mixture to the drying machine, and also introducing some of the reconditioned air from the system into the machine room for heating purposes, these features of the system further carrying out the purpose of reclaiming 20 and utilizing a large proportion of the heat of the exhaust hot air and vapors, and economy in the operation of the plant.

The invention, with other objects and advantages thereof, will be understood from 25 the hereinafter contained detail description, when considered in connection with the accompanying drawings forming part hereof and illustrating one embodiment of an apparatus for practicing the method.

Fig. 16 is a top plan view of the modified form of apparatus illustrated Figure 15.

For carrying out the improved method, the invention comprehends an apparatus including a hood arranged to extend over the 70 top of the series of heating rolls, and an exhaust apron at one side of the machine for trapping and carrying off the exhaust hot air and vapor. More particularly the invention contemplates a hood having an 75 interior chamber in the wall thereof extending completely throughout the same, with an air intake to said chamber and a discharge outlet from the chamber disposed at one side of the machine, and the supplying 80 of heated air to the interior of the chamber in the wall of the hood, said hood being adapted to serve as means for preventing escape of vapor from the top of the machine; as insulating means against the lower 85 temperature air of the machine room, and also as a distributor for heated air to the machine.

In the drawings, the invention is shown applied to a conventional form of paper drying machine of the heated roll type. 1 designates the floor of the machine room 2 of a paper drying plant, 3 the basement or room below, 4 the series of steam heated rolls of the paper making machine, 5 the pit beneath 95 the series of rolls, and 6 the paper web.

Referring to a detail description of the particular apparatus illustrated Figs. 1 to 12 of the drawings, 7 designates the hood arranged over the top of the paper making machine, and 8 the exhaust apron located at one side of the machine. The exhaust apron 8 is vertically disposed, extending throughout the length and height of the series of rolls 4, and preferably, as shown, the same 105 extends from the floor 1 to a point above the horizontal plane of the top of the series of rolls 4. The particular construction of apron shown, comprises a main wall 8^a with marginal side and end walls 8^b, 8^c, and an 110 outlet 8^d; the entrance side of the apron facing the side of the series of rolls 4.

The hood 7 extends throughout the full length of the series of rolls 4 and to either side thereof, said hood preferably extending from a point immediately adjoining the upper end of the apron 8 at the rear side of the machine to the front side thereof, in the particular exemplification illustrated in the drawings, the same being shown, extending at a downward inclination to the front side of the machine. At its front side the hood 7 is provided with a depending portion 7^a extending to the front side of the machine, said depending portion terminating short of the floor 1 leaving an open space at this point below the lower front marginal portion of the hood for the entrance of air to the machine from the machine room. The hood 7 has double walls 7^b, 7^c, spaced as 120 125 130

shown, providing an interior chamber *a* throughout the same. The interior chamber *a* is closed at the ends of the hood by end walls *7^a*, *7^b*, extending between and connected with the walls *7^b*, *7^c*. At its rear side, the hood has an air intake opening *7^f*, leading to its interior chamber *a*, said intake opening extending throughout the full length of the hood, and *9* is a distributing or feed duct extending along the rear side of the hood *7* and having an outlet co-extensive with and communicating with the intake opening *7^f* of the hood *7*. The hood *7* at its front side has an outlet from its interior chamber *a* extending throughout the length of the hood to deliver air throughout the length of the series of rolls. For this purpose, in the construction shown, the space between the upper and lower walls of the hood at its front lower marginal edge is left free, providing a longitudinally extending outlet *7^e*. The hood *7*, which is suspended over the drying section of the paper making machine by hangers from the roof trusses or from columns (not shown) may be constructed of any suitable material, the construction shown being formed of metal, galvanized iron, aluminum, or the like. The apron *8* is secured in position by any suitable means for instance by brackets (not shown) connected with the floor *1* and framing of the paper making machine.

The outlet *8^a* of the exhaust apron *8* is connected with the distributor or heated air feed duct *9* by a duct having an exhaust section *10* leading off from the apron *8*, and a return section *15*. Interposed in said duct is a combined heat recovery and air treating device *11*, and also suitable air circulating means, for instance, a fan or blower *12*, the combined heat recovery and air treating device *11* and the fan *12*, being shown located in the basement *3*, the exhaust duct section *10* having a rearwardly extending horizontal part *10^a* connected directly with the inlet end of the combined heat recovery and air conditioning device *11*, and the outlet end of the latter being directly connected with the suction side of the fan *12*.

Means is provided for heating the air after its passage through the heat recovery and air conditioning device *11*, and for this purpose the invention comprehends the use in the system, either separately or together, of a heat interchanger or device *13* for subjecting the air to indirect heating by the exhaust vapors, and also a closed or tubular heater *14*, these heating means being shown associated with the return duct section *15* which leads from the outlet side of the fan *12* to the distributing or heated air feed duct *9* of the interior chamber *a* of the hood *7*.

Referring particularly to Figs. 5 and 6 of the drawings, the particular form of heat recovery and air conditioning apparatus

shown comprises a chamber or conduit *18*, the same being shown as rectangular shape in cross section with tapering inlet and outlet portions *18^a*, *18^b* and horizontally disposed. The chamber or conduit *18* is provided with a plurality of spray devices located at intervals along the same, and means is provided for circulating water through the spray devices in successive stages, progressively starting from the outlet end portion *18^b* of the chamber or conduit. Any suitable form of spray device may be employed, the particular construction shown comprising a main pipe section *19* extending horizontally across the lower part of the chamber or conduit through one side wall thereof, and provided with vertical branch pipes *20* having a multiplicity of relatively short lateral extensions *21* which are provided with nozzles *22*.

The water circulating means includes a system of pumps *23* and a series of troughs *24* located along the bottom of the chamber or conduit *18* to receive the water from the spray devices, the spray devices being shown arranged in sets of two, a trough *24* being provided for each set of sprays. *25* designates a water supply pipe having branches *25^a*, *25^b*, leading to the first set of spray devices and *26*, *27*, are connections between the system of pumps *23* and the other sets of spray devices *19* and the troughs *24* excepting the first one of the series. Each of the troughs *24* is provided with a short overflow pipe *24^a*, that connects with a main drain pipe *24^b*, leading to any suitable point providing for the carrying away of any excess water and also for washing out the heaters and troughs. One of the tanks is provided with a fresh water inlet connection *28* whereby the tanks may be filled, when the equipment is started. *29* designates equalizer connections between the troughs *24*, and *30* is a float valve in one of the troughs for maintaining a constant water level throughout the series of troughs.

In conjunction with the spray devices, a series of closed or tubular heaters *31* is provided, the same, in the particular form of apparatus shown, being located within the influence of the vapor stream in the inlet end portion *18^a* of the chamber or conduit *18*. *32* is a pump suitably connected for circulating the water from the first of the series of troughs *24* to the inlet end of the series of tubular heaters *31*, and *33* is a conduit leading from the outlet end of the series of heaters *31* to a suitable storage tank (not shown). The system of pumps *23* and the pump *32*, which are shown located at one side of the chamber or conduit *18*, may be of any suitable type, and any suitable operating means therefor, (not shown), may be employed.

34 designates a series of baffle or elimi-

nator plates at the rear side of each set of spray devices, and 35 are deflectors extending inwardly from the walls of the chamber 18 at a rearward inclination, said deflectors acting to direct the vapor inwardly from the walls of the chamber and being arranged at intervals along the chamber, one of said deflectors being located directly in advance of each of the series of baffle plates 34.

The heat interchanger 13 may be of any suitable construction, the particular construction shown, comprising metal pipe sections or casings 13^a, 13^b, of varying diameters arranged one within the other in spaced relation providing passages 13^c, 13^d, extending close together for the treated air and the exhaust vapor, the smaller casing 13^b being interposed in the return supply duct section 15, and the larger casing 13^a connected in the exhaust duct section 10 so that the treated air from the heat recovery and conditioning device 11, passing through the inner chamber 13^c of the heat interchanger is brought in intimate relation with and heated by the exhaust vapors flowing in the opposite direction through the outer chamber 13^d of the interchanger. In the construction shown, the heating of the treated air by the exhaust vapor is further increased by arranging the supply and exhaust ducts 15, 10, close together, the supply duct having a vertical leg 15^a and a horizontal extension 15^b extending along side the vertical section 10^b and the horizontal part 10^a of the exhaust duct 10. The interchanger 13 is provided with a valve controlled intake 36 leading from the machine room into its outer exhaust vapor passage 13^d, and a valve controlled outlet 37 leading from the inner chamber 13^a to the machine room, providing for the mixing of some of the air from the machine room with the exhaust vapors, and the introduction of some of the treated conditioned air from the system to the machine room. 38, 39 designates valves or dampers of conventional form for the intake and outlet 36, 37.

The system may also be provided with a valve controlled passage 40 leading from the machine room into the distributing duct 9 providing for introduction of some of the air from the machine room into the system at this point. Any suitable type of closed or tubular heater 14 or series of such heaters may be employed. The tubular heater shown is one of the well known constructions consisting of a series of coils in which is circulated hot water or steam from any convenient source (not shown).

41 designates a branch pipe leading from the return duct section 15 for supplying conditioned air to the pit 5 for circulation at the under side of the series of heating rolls 4, said branch pipe connecting with a

distributing pipe 42 extending within the pit 5 centrally and longitudinally of the series of rolls 4, and being provided with suitable outlet orifices along the same.

The hot air and vapor from the exhaust duct section 10 is circulated through the chamber or conduit 18 of the heat recovery and air conditioning device in the direction of the arrow. The water introduced through the supply pipe 25 and circulated in succession through the sets of spray devices is discharged in fine sprays into the chamber in the path of the hot vapor stream at different points along the same in a direction counter to the flow of the exhaust vapors through the conduit, the water, being subjected to progressive stages of temperature treatment, and the air to repeated water spray treatments, with the cooler water being brought in contact with the cooler air or vapor, the warmer water with the warmer air or vapor and ultimately the warm water being brought in contact with the relatively warm air or vapor. The breaking up of the water in fine sprays in the path of the exhaust vapor provides a large amount of surface contact of the water with the exhaust air and vapors, a thorough transference of the heat of the hot vapors to the water being effected. During the passage of the vapor through the conduit, the series of baffle plates 34 serve to agitate and break up the exhaust vapor, assisting in the complete contact of the water throughout the entire body of vapor, the series of baffles also functioning to separate or extract the water from the exhaust vapors after each water spray treatment, preventing the mixture of the water in the various units and interference with the progressive temperature stages of treatment. After the successive stages of water spray treatment, the temperature of the water is further increased by its passage through the series of closed heaters 31, from which the water is finally drawn off through the conduit 33 to a suitable storage tank, (not shown), or the same may be used immediately, as desired, for various purposes.

The air after its passage through the treating chamber and being subjected to the successive water spray treatments, in a dried condition, passes to the heat interchanger 13 and the closed heater 14, is heated thereby, and then passes to the feed duct 9. From the feed duct 9, the heated reconditioned air circulates throughout the interior chamber *a* in the wall of the hood 7, passing across the same and out of said chamber through the outlet 7^c to the front side of the machine, the air being distributed all along the series of rolls. The heated air issuing from the outlet 7^c is directed laterally and inwardly toward the rolls and flows transversely of the machine and web 6 due to the forcing

effect of the fan 12 at one side and the suction at the other side through the exhaust apron 8. By this transverse flow, currents of air are induced from the machine room longitudinally of the rolls and transversely of the web through the space below the front portion 7^a of the hood and floor 1, the air from the machine room mixing with the heated air from the interior chamber *a* of the hood, and heated air is also supplied to the under side of the series of rolls 4 and web 6 through the branch pipe 41 and distributing pipe 42, so that a lateral flow of a large volume of conditioned air is maintained about the heating rolls and web. Under this condition of cross flow of conditioned air from one side of the machine, and with the hood arranged over the top of the machine, none of the exhaust vapor escapes into the machine room, the exhaust vapor being all trapped and drawn off through the exhaust apron 8 from one side of the machine. The hood 7, heated by the circulation of the heated air through its interior chamber *a*, while serving to prevent the escape of vapor into the machine room from the top of the machine also functions as a distributor for heated air to the machine, and as insulating and heat transference means, acting to prevent condensation of the vapor above the rolls and web.

During the operation of the apparatus, air from the machine room may be introduced into the system through the valve controlled intakes 36 and 40 to assist in the conditioning and tempering of the air, and heated air from the system may be introduced through the valved outlet 37 into the machine room for heating the air therein.

Provision is made in the system whereby should the air drying or dehumidifying means fail to function properly due to failure or falling off of the water supply, or failure of the pumps of the system to operate properly on account of motor or valve trouble, or the like, the exhaust hot air and vapors will not be allowed to pass back through the return duct to the drying machine but will be carried off to the outside atmosphere or other suitable place of exhaust. For this purpose the duct connecting the outlet 8^d of the exhaust apron 8 with the feed pipe 9 is provided with an emergency outlet, shown, in the present instance, as a branch pipe 50 leading from the lower part of the return duct section 15 through the wall of the drying house to the atmosphere. Damper means and automatically acting operating means therefor are provided for controlling the emergency outlet 50 and for closing the passage through the return duct section 15. The damper means may be of any suitable form, the particular construction shown comprising dampers 51, 52, consisting of a plurality of

vanes 51^a, 52^a, pivotally mounted and provided with short cranks 51^b, 52^b, to which are connected operating rods 51^c, 52^c. Various types of automatic controls or operating mechanism for the damper means may be employed. In Figures 8 to 12 of the drawings is illustrated, on an enlarged scale, one form of automatic mechanism of the well known fluid pressure actuated thermostatically controlled type having two expandable elements, one affected by the actual "dry bulb" temperature of the surrounding air, and the other affected by the lower "wet bulb" temperature of the air produced by evaporating moisture around this element, the relative expansion or contraction of the two elements being dependent upon the relation existing between the temperature and humidity of the air affecting them. The particular automatic control or damper operating mechanism shown comprises a base 53 upon which a capsular spring 54 of conventional type is mounted and connected by means of a capillary tube 55 with a sensitive member in the form of a bulb 56. A main lever 57 is fulcrumed at 58 upon uprights 59 on the base 53 and is provided with an adjustable projection in the form of a screw 60 which is maintained in contact with the capsular spring 54 by means of a spring 61 located between and engaging one end of the lever 57 and the base 53. The main lever 57 carries a capsular spring 62 connected through the medium of a capillary tube 63 with a sensitive member in the form of a bulb 64. A secondary lever 65 is pivoted at 66 upon uprights 67 extending from the main lever 57, said lever 65 being provided with an adjusting screw 68 which bears against the capsular spring 62 and is maintained in contact therewith by a spring 69 located between the two levers 57 and 65. The screw 68 carries a pointer 70 which cooperates with a suitable scale 71 provided upon the lever 65 to visibly indicate the adjustment to which the adjusting screw 68 is set.

Mounted on the base 53 is a block 72 which is provided with channels 73 and 74 connected by means of pipes 75 and 76 with a source of air or other fluid under pressure (not shown) and with a diaphragm motor 77 constructed and arranged so that its rod 77^a is moved downwardly when pressure is applied to the diaphragm, and moved upwardly under the action of a spring 77^b when the pressure upon the diaphragm is relieved. Attached to the block 72 is a valve casing 78, said casing being provided with an inlet passage 79 communicating with the channel 73 and thus with the supply of fluid under pressure, and said channel has an outlet passage 80 communicating with the channel 74 and the diaphragm motor 77. Both passages 79 and 80 are also in connection with

70

115

120

125

130

a chamber 81 in which a valve 82 of the ball type is located, the passage 79 being formed with a seat for the accommodation of the ball valve 82. The ball valve 82 is arranged to also control an exhaust passage 83 which establishes communication between the chamber 81 and the atmosphere; a stem 84 extends through and beyond the exhaust passage 83 and at its inner end engages the ball valve 82 while its outer end is adapted for engagement by a lug 85 on the secondary lever 65. The diameter of the stem 84 is such that a space exists between it and the passage 83, the space constituting the actual exhaust passage previously mentioned. The capillary tube 55 and bulb 56, and the tube 63 and bulb 64 are, in accordance with the common practice partly or wholly filled with a volatile fluid which will cause the capsular springs 54 and 62 to expand when the bulbs are subjected to an increase in temperature and to contract when the bulbs are subjected to a decrease in temperature. The wet bulb 64 is provided with a wick 86 depending into a water tank 87 to which water is supplied through a suitable pipe 88 and in which an overflow 89 is located to conduct any surplus supply of water from the tank.

The dry bulb 56 and the wet bulb 64 are both located in the system, preferably, as shown, to the outlet side of the heat recovery and air treating device 11, see Figure 5 of the drawings. The rod 77^a of the diaphragm 77 is pivotally connected at its lower end with a lever 90. The lever 90 is pivotally connected at one end to a support 91 and at its other end is pivotally connected directly with the operating rod 51^c of the damper 51 and is connected with one end of the operating rod 52^c of the damper 52 by a cable 92, said cable passing over a pulley 93, the other end of the operating rod 52^c of the damper 52 being connected with a cable 94 extending over a pulley 95 having a weight 96 secured to its other end, the arrangement being such that normally, when no air pressure is applied to the diaphragm of the diaphragm motor 77 and the lever 90 occupies the position indicated in full lines in Figure 8, the damper 51 will be closed and the damper 52 opened, and when said lever 90 is moved downwardly by the diaphragm motor 77 to the dotted line position Figure 8, the damper 51 will be opened and the damper 52 closed. When the pressure is relieved upon the diaphragm of the diaphragm motor 77 the spring 77^b actuates the diaphragm to move and hold the lever 90 in the full line position. In the upward movement of the lever 90 the weight 96 serves to actuate the operating rod 52^c of the damper 52 to open said damper.

The controller is adjusted for a certain dry and wet bulb temperature through the adjusting screw 68 and its pointer 70 cooper-

ating with the scale 71, so that under normal operating conditions of the combined heat recovery and air treating means 11 the emergency outlet 50 will be maintained closed and the passage through the return duct will be 70 opened, but should the combined heat recovery and air treating device 11, fail to function properly, so that the air passing therefrom contains a large percentage of moisture this will raise the wet bulb temperature creating a higher pressure in the capsular spring 62 and thereby expand the same. This expansion is communicated to the screw 68 and pivotally moves the secondary lever 65 to compress the spring 69 and to lift the lug 85 80 away from the end of the stem 84. It will be understood that the action of the capsular spring 62 and the movement of the secondary lever 65 are relative to the main lever 57. As the lug 85 is raised and thus 85 relieves the stem 84 from restraint, the air pressure will cause the ball valve 82 to close the exhaust passage 83 and to establish communication between the channels 79—80 by way of the chamber 81. Air pressure will thus be supplied to the diaphragm motor, which will operate through the downward movement of its rod 77^a to force the lever 90 downwardly to actuate the dampers 51 and 52, to open the emergency exhaust and close 95 the passage through the return pipe. A reduction of the wet bulb temperature back to that for which the controller is adjusted will result in relieving the pressure upon the diaphragm of the diaphragm motor and the actuation of the dampers to their normal positions.

The invention also contemplates damper operating means controlled by the pressure or flow of water to the combined heat recovery and air treating device 11 instead of by the thermostatic controller hereinbefore described. In Figure 13 of the drawings is illustrated one form of such a water pressure actuated controller, the same comprising a chamber 97 in which is a float 98 connected to one end of a lever 99, the lever 99 at its other end being pivotally connected to a side wall of the chamber 97. The lever 99 is pivotally connected, as shown, to the lower end of a valve member 100 mounted to slide within a casing 101 and carrying a valve 102 adapted to control the passage 103 of said casing. 99^a designates a stop to limit the downward movement of the lever 99. The passage 103 is connected at one side by a pipe 104 to any suitable compressed air supply, not shown, and the passage is connected at its other side by a pipe 104^a with a diaphragm motor and damper control unit (not shown in this view) the same being similar to the diaphragm motor 77 and damper control unit as in the thermostatic control previously described and illustrated in Figure 8 of the drawings. The chamber 110

97 is interposed in the water supply pipe 25 leading to the combined heat recovery and air conditioning device 11. The operation of this water pressure form of control is as follows: When the proper water supply for the combined heat recovery and air conditioning device 11 is passing through the supply pipe 25 water will accumulate in the chamber 97 and the float 98 and lever 99, 10 will maintain the valve 102 in a position to close the valve passage 103. Should the supply through the pipe 25 fail, the water in the chamber 97 will flow back through the inlet pipe connected therewith, the float 98 15 will move downwardly, and the valve 102 will be moved to a position to permit the passage of air under pressure through the passage 103 to the diaphragm motor unit to operate the same and actuate the damper 20 mechanism to open the emergency outlet 50 and close the passage through the return duct section 15. Upon resumption of the water supply through the supply pipe 25, water will again accumulate in the chamber 25 97, the float 98 will rise, and the float valve lever 99 and the valve member 100 will be actuated to move the valve 102 to closed position, cutting off the air supply to the diaphragm motor, which latter then operates 30 through its spring to return the dampers to their normal positions.

In Figure 14 of the drawings is illustrated one form of manually operable control for the damper means. In this view 105 designates a portion of the return duct section of the system, 105^a the emergency outlet, and 106 and 107 the dampers for controlling the emergency outlet and closing the passage through the return duct section 104. The 40 dampers 106—107 and the connection therebetween is the same as in the damper operating means hereinbefore described. 108—109 designate the operating rods for the respective dampers 106—107. 110 is a cable connection between one end of the operating rod 108 and one end of the operating rod 109, the cable passing over a pulley 111, and 112 is a cable connected to the other end of the operating rod 109 extending over a 50 pulley 113 and having a weight 114 secured to one end thereof. 115 designates a hand operated lever pivotally mounted at one end on a suitable support 116 and connected by a link 117 with one end of the operating rod 55 108 of the damper 106. As will be understood by swinging the hand lever 115 the dampers 106—107 can be actuated to open the emergency outlet 105^a and close the return duct section 104, and vice versa, as desired. Any suitable means is provided for limiting the throw of the hand lever 115 and for holding the same in its different positions of adjustment. In the construction shown, for this purpose, a resilient segment 60 118 is provided, the same being se-

cured to a supporting plate 119 and having notches 120—121 adapted to be engaged by a projecting portion 115^a on the lever 115.

In Figures 15 and 16 of the drawings is illustrated a modified form of the apparatus, in which no heat interchanger for indirectly heating the conditioned air by the exhaust vapor is employed, the exhaust duct section being shortened and brought directly down from the exhaust apron. Additional means is also shown for introducing additional and heated air from the system into the machine room and to other parts of the paper machine. In these views illustrating this modified construction, 122 designates the series of heating rolls, 123 the hood arranged thereover and 124 the exhaust apron at one side of the machine. 124^a is the exhaust duct section, in this instance, leading directly down from the exhaust 75 apron 124 to the combined heat recovery and air conditioned apparatus 126. 127 is the fan, 128 a closed tubular heater, and 129 is the return supply duct section leading to the distributing duct 130, which communicates 80 with the inlet 131 of the interior chamber 132 of the hood 123. 133 designates a branch pipe extending longitudinally of the machine from the distributing duct 130 for supplying heated air from the system to the machine room, and also to the paper machine at a point therein, at the wet end of the machine in advance of the series of drying rolls. 134 is the emergency outlet and 85 135—136 are the dampers for controlling the emergency outlet and the passage through the return duct section 129. The automatically acting operating means or the control for the dampers is the same as that previously described and illustrated Figures 1 to 12 of the drawings, said controlling and operating means being designated 147.

It will be noted that the invention provides for the recovery and utilization of a large proportion of the heat of the exhaust vapor, the heat recovery and conditioning of the air for re-use being effected in the same operation. The circulation of a large volume of conditioned air completely about the heating rolls and throughout the web provides for a very efficient drying of the material. Condensation upon the web and re-absorption thereby are prevented. Less steam pressure is required for the heating rolls, and the machine room is kept entirely free from the exhaust vapor, the improved method resulting in a considerable saving in the operation of the plant, increased production and a better quality of material.

While in the drawings are illustrated specific embodiments of the apparatus for practicing the improved method, it will of course be understood that changes and variations in the particular construction shown, and the embodiment of the appa-

tus in other forms, as will appeal to those skilled in the art and that fall within the scope of the appended claims may be practiced without departing from the spirit of the invention. Various forms of heat interchanging devices for indirectly heating the conditioned air by the exhaust vapors may be employed, and the number of closed heaters and the location of the same in the system may be varied to suit different conditions, as may also the number of units of the combined heat recovery and air conditioning apparatus and various forms of operating means for the damper means may be used.

Subject matter disclosed but not claimed per se in this application is claimed in our copending application filed November 3, 1922 Serial No. 598,875.

20 What we claim is:

1. The combination with a web drying machine of the heated roll type, of a hood arranged to extend over the machine, an exhaust apron located at one side of the machine to receive and draw off the vapor, and suction means connected with said apron.

2. The combination with a web drying machine of the heated roll type, of a hood arranged to extend over the machine, an apron located at one side of the machine, suction means connected with said apron, and means for delivering heated air adjacent the rolls.

3. The combination with a web drying machine of the heated roll type, of a hood arranged to extend over the machine, an apron located at one side of the machine, suction means connected with said apron, and means for delivering air at the other side of the machine.

4. The combination with a drying machine having material supporting and feeding means, of a hood arranged to extend over the material in its passage through the machine, an exhaust apron located at one side of the machine, suction means connected with said apron and means for delivering air to the material in its passage through the machine.

5. The combination with a drying machine having supporting and material feeding means, of a hood arranged to extend over the material in its passage through the machine, an exhaust apron located at one side of the machine, suction means connected with said apron, and means for delivering air at the other side of the machine opposite the apron.

6. The combination with a web drying machine of the heated roll type, of an apron located at one side of the machine, suction means connected with said apron, and means for delivering air at the other side of the machine opposite the apron.

7. The combination with a web drying ma-

chine of the heated roll type, of a hood arranged to extend over the rolls, said hood having double wall portions providing a chamber therebetween and having an outlet from said chamber leading toward the rolls, means for supplying air to the said chamber in the wall of the hood, an exhaust apron for carrying off the vapors located at one side of the machine, and suction means connected with said apron:

8. The combination with a web drying machine of the heated roll type, of a hood arranged to extend over the rolls, said hood having double wall portions providing a chamber therebetween and having an outlet from said chamber leading toward the rolls, means for supplying air to the said chamber in the wall of the hood, means for delivering heated air beneath the rolls, an exhaust apron for carrying off the vapors located at one side of the machine, and suction means connected with said apron.

9. The combination with a web drying machine of the heated roll type, of a hood arranged to extend over the rolls, said hood being provided with a chamber in the wall thereof and having a portion provided with an air outlet from the said chamber at a point at one side of the machine, an exhaust apron for carrying off the vapor located at the opposite side of the machine, means for supplying air to the chamber in the wall of the hood, and suction means connected with the exhaust apron.

10. The combination with a web drying machine of the heated roll type, of a hood arranged to extend over the rolls, said hood being provided with a chamber in the wall thereof and having a portion provided with an air outlet from the said chamber at a point at one side of the machine, an exhaust apron for carrying off the vapor located at the opposite side of the machine, means for supplying air to the chamber in the wall of the hood, means for delivering air beneath the rolls, and suction means connected with the exhaust apron.

11. The combination with a web drying machine of the heated roll type, of a hood arranged to extend over the rolls, said hood having an interior chamber in the wall thereof, and having an outlet from said chamber extending along one side marginal portion thereof at one side of the machine, an exhaust apron for carrying off the vapors extending along the other side of the machine, means for supplying air to the interior chamber in the wall of the hood, and suction means connected with said exhaust apron.

12. The combination with a web drying machine of the heated roll type, of a hood arranged to extend over the rolls, said hood having an interior chamber in the wall thereof, and having a portion extending down-

wardly along one side of the machine, said said downwardly extending hood portion having an air outlet at its lower marginal part from said chamber, an exhaust apron 5 extending along the other side of the machine, means for supplying air to the chamber in the wall of the hood, and suction means connected with said apron.

13. The combination with a web drying 10 machine of the heated roll type, of a hood arranged to extend over the rolls, said hood having an interior chamber in the wall thereof with an outlet from said chamber leading toward the machine, an exhaust apron 15 extending along one side of the machine, a duct connecting the exhaust apron with the interior chamber in the wall of the hood, air treating means interposed in said duct, and air circulating means associated with the 20 duct.

14. The combination with a web drying 25 machine of the heated roll type, of a hood arranged to extend over the rolls, said hood having an interior chamber in the wall thereof, with an air inlet to said chamber at one side of the hood, and with an outlet from said chamber at the other side of the hood, at one side of the machine, an exhaust apron 30 extending along the other side of the machine, a duct connecting the exhaust apron with the inlet to the interior chamber of the hood, air treating means interposed in said duct, and air circulating means associated with the duct.

35 15. The combination with a web drying machine of the heated roll type, of a hood arranged to extend over the rolls, said hood having an interior chamber in the wall thereof with an air inlet to said chamber at one 40 side of the hood, and with an outlet from said chamber at the other side of the hood at one side of the machine, an exhaust apron extending along the other side of the machine, a duct connecting the exhaust 45 apron with the inlet to the interior chamber of the hood, air heating means interposed in said duct, and air circulating means associated with the duct.

16. The combination with a web drying 50 machine of the heated roll type, of a hood arranged to extend over the rolls, said hood having an interior chamber in the wall thereof with an air inlet to said chamber at one side of the hood, and with an outlet from 55 said chamber at the other side of the hood, at one side of the machine, an exhaust apron extending along the other side of the machine, a duct connecting the exhaust apron with the inlet to the interior chamber of 60 the hood, means for removing moisture from the hot air and vapors interposed in said duct, and air circulating means associated with the duct.

65 17. The combination with a web drying machine of the heated roll type, of a hood

arranged to extend over the rolls, said hood having an interior chamber in the wall thereof with an air inlet to said chamber at one side of the hood, and with an outlet from said chamber at the other side of the hood 70 at one side of the machine, an exhaust apron extending along the other side of the machine, a duct connecting the exhaust apron with the inlet to the interior chamber of the hood, means for removing moisture from 75 the vapors, air heating means interposed in said duct, and air circulating means associated with the duct.

18. The combination with a web drying 80 machine of the heated roll type, of a hood arranged to extend over the rolls, said hood having an interior chamber in the wall thereof, and an outlet from said chamber at one side of the machine, an exhaust apron 85 extending along the other side of the machine, to carry off the vapors, a duct connecting the suction apron with the interior chamber in the wall of the hood, air treating means interposed in said duct, and air circulating means associated with the duct. 90

19. The combination with a web drying 95 machine of the heated roll type, of an exhaust apron extending along one side of the machine, a hood extending over the rolls provided with an interior chamber in the wall thereof, said hood extending from a point adjacent the upper end of the suction apron at a downward inclination therefrom transversely of the series of rolls to the opposite side of the machine, and having a marginal 100 depending part provided with an air outlet extending longitudinally thereof to deliver air to the rolls at that side of the machine, means for supplying air to the interior chamber in the wall of the hood at the side 105 thereof opposite the air outlet from said chamber, and suction means connected with the exhaust apron.

20. The combination with a web drying 110 machine of the heated roll type, of an exhaust apron extending along one side of the machine, a hood extending over the machine provided with an interior chamber in the wall thereof, said hood extending from a point adjacent the upper end of the apron 115 transversely of the series of rolls to the opposite side of the machine and having a marginal depending part provided with an air outlet extending longitudinally thereof to deliver air to the rolls at that side of the 120 machine, means for supplying air to the interior chamber in the wall of the hood, and suction means connected with the exhaust apron.

21. The combination with a web drying 125 machine of the heated roll type, of an exhaust apron extending along one side of the machine, a hood arranged to extend over the rolls, said hood having an interior chamber in the wall thereof, and having a portion ex- 130

- tending downwardly along one side of the machine, said downwardly extending portion terminating short of the bottom of the series of rolls leaving an opening at this 5 point for inducing a flow of air from the machine room, and said downwardly extending hood portion having an air outlet at its lower marginal part from said chamber, an exhaust apron extending along the other side 10 of the machine, means for supplying air to the chamber in the wall of the hood, and suction means connected with said apron.
22. The combination with a drying machine from which hot air and vapor are 15 given off, of means for withdrawing the hot air and vapor from the drying machine, a duct leading from said means back to the drying machine, air circulating means interposed in said duct, and air conditioning and 20 water heating means interposed in the duct, said last mentioned means including means for circulating water in a finely divided condition within the chamber in the path of the hot air and vapor to heat the water and dry 25 the air, and means for withdrawing the heated water from the chamber.
23. The combination with a drying machine from which hot air and vapor are given off, of means for withdrawing the hot 30 air and vapor from the drying machine, a duct leading from said means back to the drying machine, air circulating means interposed in said duct, and air conditioning and water heating means interposed in the duct, 35 said last mentioned means including a chamber and means for discharging water in fine sprays into said chamber in the path of the exhaust vapor in successive stages at different points along the same, said means comprising a plurality of spray devices located at intervals along the chamber, a series of troughs within the chamber to receive the water from the respective spray devices, and 40 circulating means for the water.
24. The combination with a drying machine from which hot air and vapor are given off, of means for withdrawing the hot air and vapor from the drying machine, a duct leading from said means back to the 45 drying machine, air circulating means interposed in said duct, and air conditioning and water heating means interposed in the duct, said last mentioned means including a chamber, means within the chamber for agitating 50 the vapor in its passage therethrough, and means for discharging water in a fine spray into the chamber in the path of the vapor, and means for drawing off the heated water 55 from the chamber.
25. The combination with a drying machine from which hot air and vapor are given off, of means for withdrawing the hot air and vapor from the drying machine, a duct leading from said means to the drying 60 machine, air circulating means interposed in the machine, air circulating means interposed in 65
- said duct, and air conditioning and water heating means interposed in the duct, said last mentioned means including a chamber, means for discharging water in fine sprays into the chamber in the path of the vapor in successive stages at different points along the same, and series of baffle plates located at intervals along said chamber, 70 one of said series of baffle plates being located in advance of each one of the water sprays.
26. The combination with a drying machine from which hot air and vapor are given off, of means for withdrawing the hot air and vapor from the drying machine, a duct leading from said means back to the drying machine, air circulating means interposed in the duct, said last mentioned means including a chamber, means for circulating water in a finely divided condition in successive stages to the influence of the vapor passing through 75 said chamber, said means comprising a device for discharging water in a fine spray into the chamber in the path of the vapor, a closed heater in the chamber in the path of the vapors, and circulating means for the water.
27. The combination with a drying machine from which hot air and vapor are given off, of means for withdrawing the hot air and vapor from the drying machine, a duct leading from said means back to the drying machine, air circulating means interposed in said duct, air conditioning and water heating means interposed in the duct, 80 said last mentioned means including a chamber, means for circulating water in a finely divided condition in successive stages to the influence of the vapor passing through said chamber, said means comprising means for discharging water in a fine spray into the chamber in the path of the vapor, and a closed heater in the chamber in the path of the vapors.
28. The combination with a drying machine from which hot air and vapor are given off, of means for withdrawing the hot air and vapor from the drying machine, a duct leading from said means to the drying machine, air circulating means interposed in said duct, and air conditioning and water heating means interposed in the duct, said last mentioned means including a chamber, means for discharging water in fine sprays into the chamber in the path of the vapor in successive stages at different points along the same, and series of baffle plates located at intervals along said chamber, one of said series of baffle plates being located in advance of each one of the water sprays.
29. The combination with a drying machine from which hot air and vapor are given off, of means for collecting the exhaust hot air and vapor from the drying machine, a duct leading from said collecting means back to the drying machine, air 125

circulating means interposed in said duct, and air drying means interposed in the duct, said duct having an enlarged section surrounding a smaller return section to subject the dried air to indirect heat by the exhaust vapor.

30. The combination with a drying machine from which hot air and vapor are given off, of means for collecting the exhaust hot air and vapor from the drying machine, a duct leading from said collecting means back to the drying machine, air drying means interposed in said duct, a heat interchanger interposed in said duct at the outlet side of the air drying means for subjecting the air passing from the air drying means to indirect heating by the exhaust vapor, said heat interchanger having closely associated separate passages for the moist air and vapor and for the dried air, and a valve controlled outlet from the dried air passages of the heat interchanger to the machine room.

31. The combination with a drying machine from which hot air and vapor are given off, of means for collecting the exhaust hot air and vapor from the drying machine, a duct leading from said collecting means back to the drying machine, air drying means interposed in said duct, a heat interchanger interposed in said duct at the outlet side of the air drying means for subjecting the air passing from the air drying means to indirect heating by the exhaust vapor, said heat interchanger having closely associated separate passages for the moist air and vapor and for the dried air, and a valve controlled air inlet leading from the machine room to the moist air and vapor passages of the heat interchanger.

32. The improved material drying and heat recovery system consisting in passing the hot air and vapor from a drying machine through a chamber, circulating water in a finely divided condition within the chamber in the path of the exhaust hot air and vapor to heat the water and dry the air, withdrawing the heated water for use, and conducting the dried air from the chamber back to the drying machine for drying purposes.

33. The improved material drying and heat recovery system consisting in passing the hot air and vapor from a drying machine through a chamber, circulating water in a finely divided condition within the chamber in the path of the exhaust hot air and vapor to heat the water and dry the air, withdrawing the heated water for use, and reheating the dried air from the chamber, and conducting the same back to the drying machine for drying purposes.

34. The improved material drying and heat recovery system, consisting in passing the hot air and vapor from a drying machine through a chamber, subjecting the hot

air and vapor to agitation during its passage through the chamber, discharging water in a fine spray in the path of the hot air and vapors in its passage through the chamber to heat the water and dry the air, withdrawing the heated water from the chamber for use, and conducting the air after the treatment in the chamber back to the drying machine for drying purposes.

35. The improved material drying and heat recovery system consisting in passing the hot air and vapor from a drying machine through a chamber, discharging water in fine sprays into said chamber at different points along the same in the path of the hot air and vapor in its passage through the machine, withdrawing the heated water from the chamber for use, and conducting the air from the chamber back to the drying machine for drying purposes.

36. The improved material drying and heat recovery system consisting in passing the hot air and vapors from a drying machine through a chamber, discharging water in fine sprays into the said chamber at different points along the same in the path of the hot air and vapors, and subjecting the hot air and vapors to agitation after the same has been subjected to each water spray, withdrawing the heated water from the chamber for use, and conducting the dried air back to the drying machine for drying purposes.

37. The improved material drying and heat recovery system consisting in passing the hot air and vapor from a drying machine through a chamber, discharging water in a fine spray into the chamber in the path of the hot air and vapors in successive stages at different points along the same, withdrawing the heated water from the chamber, and conducting the air after its treatment in said chamber back to the drying machine for drying purposes.

38. The improved material drying and heat recovery system consisting in passing the hot air and vapors from a drying machine through a chamber, circulating water in a finely divided condition within the chamber in the path of the hot air and vapor to heat the water and dry the air, withdrawing the heated water for use, subjecting the dried air from said chamber to indirect heating by the hot air and vapor prior to its treatment in said chamber, and conducting the dried and heated air back to the drying machine for drying purposes.

39. The improved drying and ventilating system for material drying plants consisting in supplying to a drying machine air heated to a temperature higher than the temperature of the air in the machine room, preventing the escape of the vapor from the machine into the machine room, and withdrawing the vapor from the drying ma-

chine, subjecting the hot air and vapor from the drying machine to treatment to remove moisture therefrom and to reheat the same, returning some of the heated air to the drying machine, and introducing some of the heated air to the machine room.

40. The improved drying and ventilating system for material drying plants consisting in supplying to a drying machine air heated 10 to a temperature higher than the temperature of the air in the machine room, preventing the escape of the vapor from the machine into the machine room, and withdrawing the vapor from the drying machine, 15 subjecting the hot air and vapor from the drying machine to treatment to remove moisture therefrom and to reheat the same, returning some of the treated air to the drying machine, introducing some of the 20 treated air to the machine room, and mixing air from the machine room with the treated air and supplying the mixture to the drying machine.

41. The improved drying and ventilating 25 system for paper drying plants consisting in maintaining a relatively slow flowing volume of heated air completely about the heating rolls and paper stock in its passage through the machine, preventing the escape of the 30 hot air and vapor from the machine into the machine room, withdrawing the exhaust hot air and vapor from the machine, subjecting the exhaust hot air and vapor to treatment to dry and heat the same, and 35 returning the dried and heated air to the drying machine for use over again for drying purposes.

42. The combination with a drying machine from which hot air and vapor is given 40 off, of means for collecting the exhaust hot air and vapor from the drying machine, a duct leading from said collecting means back to the drying machine, air drying means interposed in said duct and a heat interchanger imposed in said duct at the outlet side of 45 the air drying means for subjecting the air passing from the air drying means to indirect heating by the exhaust vapor.

43. The combination with a web drying 50 machine of the heated roll type, of means providing a flow of air transversely of the machine from one side thereof, and means for trapping and carrying off the vapors from the opposite side of the machine.

44. The combination with a web drying 55 machine of the heated roll type, of means providing a flow of air transversely of the machine throughout the length of the series of rolls from one side of the machine, and 60 means for trapping and carrying off the vapors from the opposite side of the machine.

45. The combination with a web drying 65 machine of the heated roll type, of means for supplying a current of air crosswise of the machine from one side thereof, and for

drawing off the vapor by suction from the opposite side of the machine.

46. The combination with a drying machine from which hot air and vapor are given off, of means for collecting the exhaust hot air and vapor from the drying machine, a duct having an exhaust section leading off from said collecting means, and a return section leading back to the drying machine, air circulating means in said duct, 70 air conditioning means interposed in the duct, said duct having an emergency outlet, and damper means for controlling said emergency outlet and for closing the passage through the return section of the duct. 80

47. The combination with a drying machine from which hot air and vapor are given off, of means for collecting the exhaust hot air and vapor from the drying machine, a duct having an exhaust section leading off 85 from said collecting means, and a return section leading back to the drying machine, air circulating means in said duct, air conditioning means interposed in the duct, said duct having an emergency outlet, and damper 90 means for controlling said emergency outlet and for closing the passage through the return section of the duct, said damper means acting to close the return duct section when the emergency outlet is opened. 95

48. The combination with a drying machine from which hot air and vapor are given off, of means for collecting the exhaust hot air and vapor from the drying machine, a duct having an exhaust section leading off 100 from said collecting means, and a return section leading back to the drying machine, air circulating means in said duct, air drying means interposed in the duct, said duct having an emergency outlet, and automatically 105 acting damper mechanism controlled by the hygrometric condition of the air in the system passing from said air drying means for controlling said emergency outlet and for closing the passage through the return section of the duct. 110

49. The combination with a drying machine from which hot air and vapor are given off, of means for collecting the exhaust hot air and vapor from the drying machine, a duct having an exhaust section leading off from said collecting means, and a return section leading back to the drying machine, air circulating means in said duct, 115 dehumidifying means interposed in the duct, said duct having an emergency outlet, and automatically acting damper mechanism controlled by the hygrometric condition of the air in the system passing from the dehumidifying means for controlling said emergency outlet and for closing the passage through the return duct section when the emergency outlet is opened. 120

50. The combination with a drying machine from which hot air and vapor are 130

- given off, of means for collecting the exhaust hot air and vapor from the drying machine, a duct having an exhaust section leading off from said collecting means, and a return section leading back to the drying machine, air circulating means in said duct, dehumidifying means interposed in the duct, said dehumidifying means including means for supplying water in a finely divided condition into the duct in the path of the exhaust hot air and vapors, said duct having an emergency outlet, and automatically acting damper mechanism controlled by the hygrometric condition of the air in the system passing from the air drying means for controlling said emergency outlet and for closing the passage through the return duct section when said emergency outlet is opened.
51. The combination with a drying machine from which hot air and vapor are given off, of means for collecting the exhaust hot air and vapor from the drying machine, a duct having an exhaust section leading off from said collecting means and a return section leading back to the drying machine, air circulating means associated with the duct, said duct having an emergency outlet, a damper controlling said emergency outlet, and a damper for closing the passage through the return duct section.
52. The combination with a drying machine, from which hot air and vapor are given off, of means for collecting the exhaust hot air and vapor from the drying machine, a duct having an exhaust section leading off from said collecting means, and a return section leading back to the drying machine, air circulating means associated with the duct, air drying means interposed in the duct, said duct having an emergency outlet, and mechanism controlled by the hygrometric condition of the air in the system passing from the air drying means for controlling said emergency outlet.
53. The combination with a drying machine from which hot air and vapor are given off, of means for collecting the exhaust hot air and vapor from the drying machine, a duct having an exhaust section leading off from said collecting means, and a return section leading back to the drying machine, air circulating means associated with the duct, air drying means interposed in the duct, said duct having an emergency outlet, and a damper for controlling said emergency outlet.
54. The combination with a drying machine from which hot air and vapor are given off, of means for collecting the exhaust hot air and vapor from the drying machine, a duct having an exhaust section leading off from said collecting means, and a return section leading back to the drying machine, air circulating means associated with the duct,
55. The combination with a drying machine from which hot air and vapor are given off, of means for collecting the exhaust hot air and vapors from the drying machine, a duct having an exhaust section leading off from said collecting means, and a return section leading back to the drying machine, air drying means interposed in the duct, said duct having an emergency outlet, a damper controlling said emergency outlet, and automatically acting operating means for the damper controlled by the hygrometric condition of the air in the system passing from the air drying means.
56. The combination with a drying machine from which hot air and vapor are given off, of means for collecting the exhaust hot air and vapor from the drying machine, a duct having an exhaust section leading off from said collecting means, and a return section leading back to the drying machine, air circulating means associated with the duct, air drying means interposed in the duct, said duct having an emergency outlet, damper means for controlling said emergency outlet and for closing the passage from the return duct section, and thermostatically controlled operating means for said damper means, said thermostatically controlled operating means including a thermostatic device influenced by the hygrometric condition of the surrounding air.
57. The combination with a drying machine from which hot air and vapor are given off, of means for collecting the exhaust hot air and vapor from the drying machine, a duct having an exhaust section leading off from said collecting means, and a return section leading back to the drying machine, air circulating means associated with the duct, air drying means interposed in the duct, said duct having an emergency outlet, damper means for controlling said emergency outlet and for closing the passage from the return duct section, and thermostatically controlled operating means for said damper means, said thermostatically controlled operating means including a thermostatic device influenced by the hygrometric condition of the surrounding air located in the system to the outlet side of the air drying means.
58. The combination with a drying machine from which hot air and vapor are given off, of means for collecting the exhaust

- hot air and vapor from the drying machine, a duct having an exhaust section leading from said collecting means, and a return section leading back to the drying machine, an apron extending along the other side of the machine to trap and carry off the vapor, means for supplying air to the chamber in the wall of the hood, and suction means associated with said exhaust apron.
62. The combination with a web drying machine of the heated roll type, of a hood arranged to extend over the rolls, the hood being provided with a chamber in the wall thereof, and said hood having a marginal portion projecting beyond the rolls at one side of the machine provided with a longitudinally extending outlet from the chamber in the wall of the hood for discharging air inwardly across the space between the same and the adjacent portion of the rolls, an apron extending along the other side of the machine to trap and carry off the vapor, means for supplying air to the chamber in the wall of the hood, and suction means associated with said apron.
63. The combination with a web drying machine of the heated roll type, of a hood arranged to extend over the rolls, means providing for discharging air across the space between the hood and the rolls at one side of the machine, an apron extending along the other side of the machine to trap and carry off the vapor, and suction means associated with said apron.
64. The combination with a web drying machine of the heated roll type, of a hood arranged to extend over the rolls, an apron located at one side of the machine, suction means associated with said apron, and means for discharging air adjacent the rolls at a point below the same.
65. The combination with a drying machine having material supporting and feeding means, of a hood arranged to extend over the material in its passage through the machine, an apron located at one side of the machine to trap the vapor, and suction means associated with said apron.
- In testimony whereof we hereunto affix our signatures.

EDWARD L. HOGAN.
